(21) Appl. No.: **29/366,919**

The novel ornamental design for a rotational light-emitting diode directed array light bulb assembly, as shown and described.

(22) Filed: **Jul. 31, 2010**

DESCRIPTION

(51) LOC (9) Cl. **26-04**

FIG. 1 is a front perspective view showing the rotational light-emitting diode directed array light bulb assembly, according to the novel design;

(52) U.S. Cl. **D26/2**

FIG. 2 is a front elevation view thereof;

(58) Field of Classification Search D26/1-4;

FIG. 3 is a left side elevation view thereof;
